SAFETY CONTROL CORPORATION, OF PHILADELPHIA, PENNSYLVANIA

SAFETY DEVICE FOR MOTION PICTURE PROJECTING MACHINES

Application filed July 9, 1927. Serial No. 204,454.

My invention relates to safety devices for motion picture projecting machines and more particularly to a device which permits a dowser to fall by gravity into light obstructing position; and to break the motor circuit in case the film should break, clog or tear, or in case any belt of the driving mechanism breaks or the motor current becomes excessive or fails.

10 The object of my invention is to provide means for actuating such a safety device in case of defective operation as enumerated above.

According to the invention the safety means comprises, in combination with means for holding the dowser out of light obstructing position, an electro-magnet normally energized and which, when deenergized by defective operation of the film across the 20 aperture, operates to trip the means to permit the dowser to fall by gravity into light obstructing position.

The drawings illustrate embodiments of the invention and the views therein are as follows:

Figure 1 is a side view of a preferred embodiment of my invention showing same attached to a safety device which is shown mounted upon a fragment of a projector cone; the housing of the attachment being broken open in order to expose the contents thereof.

Figures 2 and 3 are, respectively, detail views of a sleeve and plunger which form parts of the device shown in Figure 1.

Figure 4 is a view similar to Figure 1 but showing a modified form of my invention; one of the magnet coils being broken open in order to expose the core and plunger there- 40 in, and

Figure 5 is a detail view of a modified form of armature adapted to be used in the attachment shown in Figure 4.

Figure 6 is a view similar to Figure 1 but showing still another modification of my invention, and

Figure 7 a rear view of the safety device shown in Figures 1, 4 and 6, to which is attached one of the several forms of my invention; the cover of the safety device being

omitted and the housing of the attachment being broken open in order to expose the contents thereof.

Figure 8 is a sectional view of the complete electro-magnet housing, taken on a plane indicated by the line 8-8 of Figure 7, and

Figure 9 a fragmentary sectional view taken on line 9-9 on Figure 7; the dowser handle being omitted.

Figure 10 is a wiring diagram showing the relation between my invention and the various units which comprise a complete fire preventing apparatus.

Referring now more particularly to Figures 1, 4, 6 and 7, in which my invention is shown attached to a safety device 9 having a casing 10 provided with a base 11 by means of which it may be secured to the cone 12 of a projecting machine lamp housing. The rear side of casing 10 is closed by a cover 13 and a shaft 14 and is journaled therein and in the front of casing 10. An electro-magnet 15, adapted to be energized whenever the film breaks, is secured to the inside of casing 10. A mercury switch 16 is mounted on a spring bearing 17 which has its free end supported against the spring action of the bearing by a cam 18 secured to shaft 14. A dowser handle 19 is fixed to the outer end of shaft 14 and carries a dowser plate 20 which is adapted to be swung between the lamp housing and the film passing through the projector in case the film should cease to move from any cause.

Dowser plate 20 is held out of light obstructing position by a latch 21, as shown in detail in the co-pending application of Feeney et al., filed March 3rd, 1927, Serial No. 172,294. This latch has a trip arm 22 formed integral therewith and its outer end extends outside of the casing 10. An armature 23 is hinged to casing 10 just below magnet 15 and has a bifurcated end engaging a screw inserted in the side of latch 21, so that magnet 15, when energized, will attract armature 23 and trip latch 21 and allow dowser 20 to fall into light obstructing position.

As dowser plate 20 swings downwardly, cam 18 is rotated so that its flat face is uppermost and the free end of spring bearing 17 is thus allowed to move downwardly and tilt mercury switch 16 so that the mercury contained in the switch moves away from the switch points and opens the circuit at this point; mercury switch 16 being so connected that the breaking of the circuit at this point will cause the stopping of the motor, as will hereinafter be described. As shown in Figure 7, I provide four binding posts in the upper part of casing 10 of which the two outer ones are connected to the two terminals of switch 16 and the two center ones to opposite ends of the winding of electro-magnet 15.

In order to actuate safety device 9 and cause dowser 20 to intercept the rays of light passing through the film in case the film should cease to move due to the breaking of a belt or failure of power to the motor, I provide an attachment 24 which preferably includes a housing 25 attached to casing 10. In Figure 1, I have shown housing 25 enclosing a solenoid which consists of an electro-magnet 26, a sleeve 27, a plunger 28 and a magnet frame 29.

Sleeve 27 extends upwardly through the bottoms of housing 25 and frame 29 and fits in the center of magnet 26. It is provided with a slit 30, which tends to prevent eddy currents being set up when magnet 26 is energized, and with a flange 31 through which screws 32 may be passed and threaded into the bottom of frame 29 for securing the solenoid in casing 25. Plunger 28 preferably consists of an armature 33, made of magnetic material and laminated or provided with a slot 34, a stem 35 of non-magnetic material, and a head 36.

A support 37, secured to casing 10 in any suitable manner, has a lever 38 pivoted to its lower end and engages the underside of head 36 by its one end and engages the lower end of the trip arm 22 by its other end. When the magnet 26 is energized, armature 33 will be drawn into the same and the head 36 will assume the position shown in Fig. 1, but, when the magnet is deenergized, plunger 28 will fall by gravity and head 36 will pull the end of the lever 38 downwardly and cause the opposite end to raise trip arm 22, thus permitting the dowser 20 to fall by gravity into a light obstructing position.

In Figures 4, 7 and 8, I have shown a modification having a housing 25^a which is quite similar to housing 25 and provided with a rib 39 to which the core 40 of an electromagnet 41 may be attached by means of screws or bolts. Core 40 is bifurcated to form a core part 42, which extends but part way through its coil, and a core part 43, which extends above its coil. A support 44 is secured to the bottom of housing 25^a, extends upwardly

along one side of magnet 41, and has a magnet armature 45 hinged to its upper end and abutting the under side of trip arm 22.

Armature 45 is adapted to be moved upwardly by means of a spring which may be of any desired type but has been shown as a bent spring 46 having one end coiled about a pin 47, by means of which armature 45 is hinged to support 44, and having its outer end engaging armature 45, as by contacting with a screw or other projection extending from the side of the armature. When magnet 41 is energized, core part 43 will attract armature 45 and core part 42 will attract a plunger 48 hinged to armature 45. When practical, the several parts should be carefully machined and assembled so that the top of core part 43 will abut the underside of armature 45 and the top of core part 42 abut the bottom of plunger 48 in order to eliminate any danger of the magnet heating or the armature chattering; it being understood that the attachment should be made as small and compact as possible.

As long as magnet 41 is energized, it is evident that it will hold armature 45 against the action of spring 46 but, as soon as it is deenergized, spring 46 will swing armature 45 upwardly and raise trip arm 22, releasing dowser plate 20 to permit it to fall by gravity into light obstructing position. In order that spring 46 may not swing armature 45 beyond a certain point, I provide a stop 49 secured to the side of casing 10 and adapted to limit the upward movement of the lever so that it does not move outside the field of attraction of magnet 41.

Instead of hinging plunger 48 to armature 45, as shown in Figure 4, I sometimes employ an armature 45^a which has a plunger 48^a fixed rigidly thereto or formed integral therewith, as shown in Figure 5. This armature is employed and functions in the same way as does armature 45 and plunger 48 but, in order that plunger 48^a may reciprocate in the bore of magnet 41, it is necessary to slightly taper the forward side of its lower end.

In Figure 6, I have shown a device very similar to that shown in Figure 4 and having a number of like parts which have been designated by like reference numerals, while the parts which are similar to those in Figure 4 have been designated by the same numerals to which the exponent "a" has been added. In this modification, the core 42^a of a plain electro-magnet 41^a is provided with two core parts 43 which are adapted to abut the bottom of armature 45 and, when the magnet is energized, hold same against the action of spring 46. The function and operation of this modification are the same as those of the modification shown in Figure 4 and, is in the former case, the parts should be so carefully made and assembled that the

tops of both core parts 43 abut the underside of armature 45.

Referring now to Figure 10, in which a method of wiring a complete fire preventing apparatus is shown, 50 represents a switch which is adapted to make connection with a source of electrical energy, as indicated by the power line A—B. A wire 51 connects one pole of switch 50 to one side of the motor M, 10 which drives the projecting mechanism of the motion picture projector, and a wire 52 connects the other side of motor M to one side of a switch 53, which forms a part of a switch unit 54, while a wire 55 connects the 15 other side of switch 53 to the opposite pole of switch 50, thus completing the motor circuit.

One part of switch 53 is mounted on base 56 of switch unit 54 while its other part is 20 carried by an armature 57 hinged to a bracket on base 56. Switch 53 is held in closed position by a magnet 58 against the action of a spring 59. One part of a switch 60 is mounted on base 56 while its other part 25 is carried by a lever 61 hinged to a bracket on base 56; switch 60 being held in closed position by a spring 62. Motor M drives the projecting mechanism of the projector through belts 63 and 64 which support rollers 65 and 66 respectively. Roller 65 is rotatably mounted on a lever 67 hinged above lever 61 and carrying an arm 68 which is adapted to swing the end of lever 61 downwardly and open switch 60 if belt 63 should 35 break and allow roller 65 to fall. If belt 64 should break, roller 66 would fall upon the end of lever 61 and open switch 60.

A wire 69 connects one side of switch 60 to wire 51 and a wire 70 connects its other side 40 to one end of the winding of electro-magnet 58. A wire 71 connects the other end of the winding of magnet 58 to one terminal of mercury switch 16 while the other terminal of mercury switch 16 is connected to wire 55 by 45 means of a wire 72. It is thus evident that, as long as switches 50, 16 and 60 are closed, a current may flow through magnet 58 and allow it to hold switch 53 in closed position.

One end of the primary winding of a 50 transformer 73 is connected by a wire 74 to wire 51 and its other end connected by a wire 75 to wire 52 so that current will flow through the primary of transformer 73 whenever switch 53 is closed. One end of the 55 secondary winding of transformer 73 is connected by a wire 76 to one end of the winding of electro-magnet 15 and the other end of the winding of this magnet is connected by a wire 77 to one side of switches 78 and 79 which are normally open and adapted to be 60 closed by the breaking of the film. The other sides of these switches are connected to the other end of the secondary winding of transformer 73 by means of a wire 80. It will thus be seen that, if either switch 78 or 79 is closed

by the breaking of the film, the current set up by transformer 73 will pass through magnet 15, energize same and cause it to attract armature 23 and trip latch 21, thus causing 70 dowser 20 to fall and intercept the rays of light passing through the film. As dowser plate 20 falls, cam 18 is rotated and spring bearing 17 tilts mercury switch 16 so as to interrupt the flow of current therethrough, thus deenergizing magnet 58 and allowing 75 spring 59 to open switch 53 and stop the motor.

One end of the winding of the magnet in attachment 24 is connected by a wire 81 to wire 80, intermediate switch 78 and transformer 73, while the other end of its winding is connected by a wire 82 to wire 76 so that the current set up by transformer 73 will flow through this magnet and energize it. If the attachment shown in Figure 1 is 85 employed, plunger 28 will be held in its upper, or inoperative, position by the power of magnet 26. Should switch 53 be opened, the flow of current through the primary of transformer 73 will be interrupted and consequently no current will be set up by its secondary and magnet 26 will be deenergized, thus allowing plunger 28 to fall, swing lever 38 against trip arm 22 and actuate safety device 9. 90

If either of the attachments shown in Figures 4 or 6 is employed, the current set up by transformer 73 will energize magnet 41 or 41^a and cause it to hold armature 45 against the action of spring 46. Should switch 53 be 100 opened and magnet 41 or 41^a deenergized, spring 46 will swing armature 45 upwardly and raise trip arm 22, thus actuating safety device 9. 95

Assuming that the projecting machine is 105 in condition for operation and switch 50 closed, current will flow from switch 50 through wire 51, motor M, wire 52, switch 53, wire 55 to switch 50, thus providing power for the motor and causing the projector to be 110 operated. At the same time, current will flow from switch 50, through wire 51, wire 74, primary of transformer 73, wire 75, switch 53 and wire 55 to switch 50, thus allowing the transformer to set up a current in its secondary which flows through wire 80, wire 81, the electro-magnet in attachment 24, wire 82 and wire 76, to the transformer; thus keeping the electro-magnet energized and preventing trip arm 22 from being raised but, if switch 53 120 should be opened by the breaking of a belt or failure of power to the motor, this flow of current would be interrupted and the magnet deenergized, causing the actuation of device 9. 125

Current flows from switch 50 through wire 51, wire 69, switch 60, wire 70, electro-magnet 58, wire 71, mercury switch 16, wire 72 and wire 55 to switch 50, thus energizing magnet 58 so that it holds armature 57 against the 130

action of spring 59 and allows switch 53 to remain closed. If belt 63 or belt 64 should break or the supply of electrical energy fail, magnet 58 will be deenergized and switch 53 opened, thus stopping the motor, deenergizing the magnet in attachment 24 and actuating safety device 9.

If a film should break, either above or below the aperture plate, switch 78 or switch 79 will be closed by suitable means on the projector and not shown and thus will complete the electrical circuit and current will flow from one end of the secondary winding of transformer 73 through wire 80, switch 78 or 79, wire 77, electro-magnet 15, wire 76, to the other end of the secondary winding, thus energizing magnet 15 and causing it to attract armature 23 and trip latch 21 which allows dowser 20 to fall and rotate cam 18 and cause spring bearing 17 to tilt mercury switch 16 forwardly and open the circuit at this point which will cause magnet 58 to be deenergized and allow spring 59 to open switch 53.

With an apparatus arranged and electrical- 25 ly connected as above described, the rays of light passing through a film will be inter- 30 cepted and the motor stopped in case any- 35 thing should happen to the film such as break- 40 ing, tearing, or clogging, or should the pro- 45 jecting mechanism cease to function from any 50 cause, such as the breaking of a belt or the 55 failure of power.

Of course, the safety devices herein illus- 35 trated may be modified and changed in va- 40 rious ways without departing from the in- 45 vention herein set forth and hereafter 50 claimed.

I claim:

1. Fire prevention apparatus for a motor 49 driven projecting machine comprising a safety device having a dowser, a magnet in said device adapted to be energized when the film breaks, tears, clogs, etc., a trip arm for holding the dowser out of light obstructing position when the magnet is deenergized and for permitting the closing of said dowser when the magnet is energized, a make and break switch for maintaining the motor circuit when the dowser is raised out of light obstructing position, an auxiliary magnet associated with said safety device and normally energized when the dowser is out of light obstructing position, an armature for said auxiliary magnet, means associated with said auxiliary magnet, means associated with said armature for operating the trip arm to release the dowser upon the deenergization of said auxiliary magnet, a switch in the circuit of said auxiliary magnet, a switch arm adapted to be pressed downward when a motor belt breaks to thereby open the last named switch to deenergize said auxiliary magnet and release said armature to thereby operate said trip arm and release said dowser, and means operated by the falling dowser to tilt said mercury switch for opening said motor circuit.

2. Fire prevention apparatus for a motor 60 driven projecting machine comprising a safety device having a dowser, a magnet in said device adapted to be energized when the film breaks, tears, clogs, etc., a trip arm for holding the dowser out of light obstructing position when the magnet is deenergized and for permitting the closing of said dowser when the magnet is energized, a make and break switch for maintaining the motor circuit when the dowser is raised out of light

safety device having a dowser, a magnet in said device adapted to be energized when the film breaks, tears, clogs, etc., a trip arm for holding the dowser out of light obstructing position when the magnet is deenergized and for permitting the closing of said dowser when the magnet is energized, a make and break switch for maintaining the motor circuit when the dowser is raised out of light obstructing position, an auxiliary magnet associated with said safety device and normally energized when the dowser is out of light obstructing position, an armature for said auxiliary magnet, means associated with said armature for operating the trip arm to release the dowser upon the deenergization of said auxiliary magnet, a switch in the circuit of said auxiliary magnet, a switch arm adapted to be pressed downward when a motor belt breaks to thereby open the last named switch to deenergize said auxiliary magnet and release said armature to thereby operate said trip arm and release said dowser, and means operated by the falling dowser to tilt said first named switch for opening said motor circuit.

3. Fire prevention apparatus for a motor driven projecting machine comprising a safety device having a dowser, a magnet in said device adapted to be energized when the film breaks, tears, clogs, etc., a trip arm for holding the dowser out of light obstructing position when the magnet is deenergized and for permitting the closing of said dowser when the magnet is energized, a tiltably mounted mercury switch for maintaining the motor circuit when the dowser is raised out of light obstructing position, an auxiliary magnet associated with said safety device and normally energized when the dowser is out of light obstructing position, an armature for said auxiliary magnet, means associated with said armature for operating the trip arm to release the dowser upon the deenergization of said auxiliary magnet, a switch in the circuit of said auxiliary magnet, a switch arm adapted to be pressed downward when a motor belt breaks to thereby open the last named switch to deenergize said auxiliary magnet and release said armature to thereby operate said trip arm and release said dowser, and means operated by the falling dowser to tilt said mercury switch for opening said motor circuit.

4. Fire prevention apparatus for a motor 120 driven projecting machine comprising a safety device having a dowser, a magnet in said device adapted to be energized when the film breaks, tears, clogs, etc., a trip arm for holding the dowser out of light obstructing position when the magnet is deenergized and for permitting the closing of said dowser when the magnet is energized, a make and break switch for maintaining the motor circuit when the dowser is raised out of light

obstructing position, an auxiliary magnet associated with said safety device and normally energized when the dowser is out of light obstructing position, an armature for said auxiliary magnet, a lever pivotally mounted and having its one end engaging the armature and its other end engaging the trip arm, means associated with said armature for operating the trip arm to release the dowser
10 upon the deenergization of said auxiliary magnet, a switch in the circuit of said auxiliary magnet, and a switch arm adapted to be pressed downward when a motor belt breaks to thereby open the last named switch to de-
15 energize said auxiliary magnet and release said armature to thereby operate said trip arm through the medium of said pivoted lever to release said dowser.

In testimony whereof I have signed my
20 name to this specification.

JOSEPH ELLIS COHEN.
